United States Patent Office

Des. 191,999
Patented Dec. 26, 1961

191,999

FIREPLACE

Alfred C. Haralson, 7712 Beacon Ave., Seattle, Wash.

Filed May 26, 1961, Ser. No. 65,354

Term of patent 14 years

(Cl. D81—7)

FIG. 1.

FIG. 2.

FIG. 3.

FIG. 4.

FIG. 5.

FIGURE 1 is a perspective view of a fireplace showing my new design;

FIGURE 2 is a top plan view thereof;

FIGURE 3 is a side elevational view thereof taken from the left of FIGURE 1;

FIGURE 4 is a side elevational view thereof taken from the right of FIGURE 1; and

FIGURE 5 is a bottom plan view thereof.

It is to be noted that the rear of the fireplace is substantially plain.

I claim:

The ornamental design for a fireplace, as shown and described.
